United States Patent

Des. 242,308
Patented Nov. 16, 1976

242,308

ARMCHAIR OR THE LIKE

Joseph E. Adkinson, 3807 Leland St.,
Chevy Chase, Md. 20015

Filed Apr. 23, 1974, Ser. No. 463,285

Term of patent 14 years

Int. Cl. D6—01

U.S. Cl. D6—68

FIG. 1

FIG. 2

FIG. 3

FIG. 1 is a perspective view of a chair showing my design;

FIG. 2 is a back elevational view of the chair of FIG. 1; and

FIG. 3 is a side elevational view of the chair of FIGS. 1 and 2.

I claim:

The ornamental design for an armchair or the like, substantially as shown.
